UNITED STATES PATENT OFFICE

HANS COERPER, OF STATEN ISLAND, NEW YORK, ASSIGNOR TO INTERNATIONAL COMBUSTION ENGINEERING CORPORATION, OF NEW YORK, N. Y., A CORPORATION OF DELAWARE

BOILER FURNACE

Application filed December 3, 1925. Serial No. 72,871.

This invention relates to boiler-furnaces, particularly for stationary installations burning fuel in finely divided form such as pulverized coal.

One of the primary objects of the invention is to provide a novel arrangement of boiler-furnace wherein I am enabled to generate a large quantity of steam with but a small portion of the evaporating area heretofore required in standard practice.

Other and more specific objects and advantages will appear hereinafter.

How the foregoing, together with such other objects and advantages as are incident to my invention, are realized, is illustrated in the accompanying drawings, wherein

Fig. 1 is a vertical section thru an installation embodying my improvements in preferred form, and

Fig. 2 is a sectional view illustrating a detail of my invention.

Referring now to Fig. 1 of the drawings, the reference character A denotes the combustion chamber. The combustion space of this chamber is defined by a front water wall *a*, side water wall *b*, and a rear water wall *c*. These water walls are composed of upright tubes 7 having longitudinally extending fins 8 welded or otherwise secured thereto, the fins and tubes cooperating to form a practically continuous metallic wall. The fins on the tubes constituting the water wall *c* extend only part way from the upper end of said tubes toward the bottom leaving the waste outlet B toward the lower portion of the combustion chamber at the rear. That is to say, spaces are provided between the tubes of the rear water wall immediately above the bridge wall 9, thru which spaces the waste products leave the combustion space.

The top of the combustion space is defined by a water wall *d*, the bottom of the combustion space is defined by a water screen *f*. The water screen is composed of tubes sufficiently widely spaced apart to permit the gravitating refuse leaving the fuel and flame stream to flow freely therebetween into the ash pit *g*, the screen serving to cool the refuse particles while in transit to a non-molten state. The lower ends of the tubes of the front water

wall *a* pass outwardly thru the sheathing 10 for connection into the drum or header 11. The upper ends of the tubes of this wall pass outwardly thru the roof sheathing or arch sheathing 12 to the header 13. The tubes of the upper water wall extend from the header 13 to the drum 14. The tubes of the water screen lead from the drum or header 11 to the junction blocks 15 into which junction blocks the lower ends of the tubes of the rear water wall are connected. The upper ends of the tubes of the rear water wall connect into the header 16 which in turn is connected to the drum 14. Water is supplied from the lower or mud drum 17 to the header or drum 11 by means of a suitable downcomer or downcomers 18. Thus circulation is from the drum 17 to the drum 11 and thence upwardly thru the screen and the rear water wall and front water wall and the top water wall to the drum 14 and thence to the drum 17 thru certain of the bank of tubes *h*. The ends of the tubes of the side water walls extend outwardly for connection into the headers 19 and 20 respectively. A downcomer or downcomers 21 connect the drum 14 to the lower end of the headers 20 and the upper end of the headers 19 are connected to the drum 14 by the upcomer connections 22.

The furnace shaped boiler thus described is subjected to radiant heat and, therefore, will absorb heat at a very high rate and produce an enormous quantity of steam by virtue thereof. Hence, I am enabled to provide a boiler-furnace of very small size in comparison to standard practice wherewith to produce a very large quantity of steam. Because of the high rate of heat transmission, the tendency of the water walls is to lower furnace temperature and to interfere with proper combustion. To meet this condition I supply the fuel and air required for combustion in such manner as to produce turbulent combustion and a short flame, accompanied by an increase in furnace temperature head.

To this end I supply the fuel by two sets of burners 23 and 24 which may be directly or indirectly supplied with powdered coal and carrying air therefor. These sets of burners are directed so as to cause the enter-

ing sheets of fuel to impinge upon one another with violent mixing and turbulence. The additional air required for combustion is supplied thru the horizontal ducts 25 extending around the upright water walls. Highly preheated air, heated in a manner to be hereinafter described, is introduced into these ducts from the breaching or casing 26 and enters the combustion space thru spaces 27 5 provided by interrupting the fins on certain of the tubes. This air is preferably introduced under pressure as by means of the fan, (not shown) which fan forces the air thru the preheater 28 into the breaching or casing 26. 10 This additional air mixes with the fuel, adding to the turbulence and producing violent and intense combustion, with a flame of high temperature, the fuel being burned with a short flame, which is also necessary by virtue 15 of the fact that the waste outlet is toward the bottom of the combustion space. 20

The amount of evaporating surface for the combustion chamber is such that the waste gases leave at a high temperature and enter 25 the bank of tubes *h* which is baffled in the manner indicated. From this pass the gases are eventually led to a second bank of tubes *i* and from there to the offtake 29 in which the preheater is located. The bank of tubes 30 *h* and *i* constitutes in effect economizer sections. The tubes of the bank *h* are connected to the drums 14 and 17, the tubes of the bank *i* connect the drum 30 with the drum 17 and tubes 31 connect the drums 14 and 30. Thus, 35 altho all the boiler elements are in a sense connected into one system, local circulation occurs thru the banks *h* and *i* and 31, as it does in the units defining the combustion space. Channels 25 at the rear of the combustion space are formed by the divisions 40 33, the water wall *c* and the first row of the bank of tubes *h* which row is provided with fins 32 for this purpose.

A high degree of preheat of the combustion air is obtained because of the high temperature at which the gases leave the bank 45 of tubes *i*. In this connection it is to be noted that for a given output, the size of the boiler as a whole will be very much smaller 50 than that which would be required in a standard practice, in consequence of which not only the tubes of the upright walls of the combustion chamber, but also the tubes of the banks *h* and *i* will be of comparatively short 55 length, besides which the number of tubes employed in the banks *h* and *i* will not be large.

What I claim is:

The combination with a finely divided fuel 60 burning furnace of a boiler including two rows of substantially upright tubes defining combustion space, header means at the lower end of the tubes of each row, a row of tubes extending across the lower portion of the furnace and connecting the header means of one

upright row with the header means of the other upright row, economizer means including connected upper and lower drums, the upper ends of the upright rows of tubes being connected to said upper drum and down-comer means connecting said economizer means to one of said headers.

In testimony whereof, I have hereunto signed my name.

HANS COERPER.
